UNITED STATES PATENT OFFICE.

KARL GUIDO ARTHUR UHLIG, OF LEITELSHAIN, GERMANY.

RAIL AND RAILWAY-TRACK.

SPECIFICATION forming part of Letters Patent No. 608,732, dated August 9, 1898.

Application filed December 30, 1897. Serial No. 664,776. (No model.)

To all whom it may concern:

Be it known that I, KARL GUIDO ARTHUR UHLIG, a subject of the King of Saxony, and a resident of Leitelshain, near Crimmitzschau, 5 Kingdom of Saxony, Germany, have invented new and useful Improvements in Rails and Railway-Tracks, of which the following is a full, clear, and exact description.

The present invention relates to railway-tracks; and it consists in the details of construction hereinafter set forth, and particularly pointed out in the claims, and in order to render the present specification more easily intelligible reference is had to the accompanying drawings, in which similar letters of reference denote similar parts throughout the several views.

Figure 1 is a cross-section through the rail; Fig. 2, a side elevation, and Fig. 3 a side elevation of a portion of the track.

According to the present invention the rail is made in two parts A and B, the former comprising the head, having two downwardly-extending webs or flanges C C arranged a 25 slight distance apart and extending to the top of the flange or foot B of the rail, and the latter comprising the said flange or foot B and having a central longitudinal upwardly-extending flange a, which is inclosed 30 by the two flanges C C of the head A. The two parts are fixed together by means of screws s, and the ends of the flanges C C are beveled off and fit in corresponding recesses in the flange B, so as to prevent their lateral 35 extension.

The rail-spikes n and the hooks h alternate with each other along the line of rails, and the heads of the former are cut away, so that the end of the flanges C C may close down onto the 40 cut-away part, thus securing the spike on the one hand and being prevented by the projecting remaining part of the said spike-head p from bulging outwardly.

The main advantage of rails of the present

construction and of tracks constructed by 45 means of such rails is that the joints of the two parts of the rails may be displaced as regards each other, as is shown at Fig. 3. The sections of the flange-rail B are joined at x, which joint is covered by the head rail A, the 50 sections of which are joined at points where no joint of the flange or foot rail occurs. Thus perfectly noiseless traveling will result from the employment of rails of the present description.

The rib a is slightly tapered toward its upper end to insure the ends of the flanges C C resting on the foot-plate B.

The cross-section of the rail may be varied to suit particular circumstances, the present 60 invention not being confined to any particular section of rail.

I claim as my invention—

1. The combination of a rail-section having the rail-head and downwardly-extending longitudinal flanges, a foot-section having upwardly-extending longitudinal rib, means for securing the parts together as specified, and spikes to penetrate said foot-section, said spikes having their heads lying partly underneath the lower edges of the head-rail flanges substantially as described.

2. The combination of a rail having a head-section and a foot-section and means for combining the two sections as specified, spikes to penetrate said foot-section having their heads partly cut away and lying underneath the downwardly-extending head-rail, the remainder of said spike-head projecting upwardly at the side of said rail substantially as described.

In testimony whereof I have signed my name to this specification in the presence of two subscribing witnesses.

KARL GUIDO ARTHUR UHLIG.
